UNITED STATES PATENT OFFICE.

CARL W. CHERRY, OF SAN FRANCISCO, CALIFORNIA.

HOME SAVINGS BANK.

Application filed July 27, 1925. Serial No. 46,428

This invention refers to savings banks, principally of the smaller type issued by banking institutions to promote savings amongst children at home.

5 The principal object of the invention is to provide a bank of this kind which is proof against being opened by anyone except through the application of special magnetic means, such means to be in the custody of 10 the institution only.

Other objects are simplicity of construction of a device of this kind together with a shell structure which has but one flat surface upon which to stand it, and when stood there- 15 on will effect a concealment of the coin slot or other evidence denoting it to be a bank.

The accompanying drawing shows the preferred embodiment of my invention.

Figure 1 is a perspective view of the bank 20 with the coin receiving flat end uppermost.

Figure 2 is a plan of the circular head with most of the upper plate and the door removed showing the lock.

Figure 3 is an elevation of Figure 2 in 25 section taken along the line 3-3 of Figure 2, and also showing a portion of the shell rolled over the upper plate.

Figure 4 is a view of the under side of the 30 door.

Figure 5 a detached view of the bolt throw- 35 ing spring member, and

Figure 6 a detached view of one of the 40 bolts.

Briefly described, my bank consists of a 45 bowl shaped shell 1 with a head plate 2 at the open end having a hinged door 3 and a coin receiving slot 4.

The head is permanently crimped in place 50 by the shell edge being rolled over it as shown at 5, and the hinged door is normally locked in closed position by a pair of spring actuated bolts 6.

The bolts are of iron or steel and inacces- 55 sible from without the bank and may only be drawn for opening the door by means of powerful magnets applied at the right spots to the outer casing. The special magnet ar- 60 rangement for pulling the bolts constitutes a separate invention filed by me under Serial No. 46,429, July 27, 1925.

In more detail the casing or shell 1 is pref- 65 erably of non-magnetic material, such as brass, and my preferred form is bowl shaped as shown, ribbed for extra stiffness. The 70 head comprises an upper plate 2 and a lower

plate 2; also of brass, and spaced by spacers 7, 8 all secured together by screws or rivets 9.

The door 3 is hinged to the head preferably by engaging an upturned lip 10 formed on the lower plate 2', and is spring actuated to 60 swing outwardly through means of a small wire spring 11 passing through a hole in the lip 10 and secured to the under plate by a rivet head 9.

This door has a pair of hasps 12 project- 65 ing from its under side adapted to receive the tine 13 of the sliding bolts 6.

These bolts are of steel or iron and are guided for sliding action in a channel formed by bending up the lower plate as indicated 70 in Figures 2 and 3 and each bolt is provided with an enlarged head 6' for acting on by the magnets and which heads also limit the out- 75 ward movement of the bolts by striking the casing at a time when the door hasps are free for withdrawal from the hasp slots 14 so that as the bolts are simultaneously pulled by magnetic means the spring door will fly open. Figure 2 shows the lower bolt as pulled open by the pull of an electric magnet 19.

The bolts are spring actuated by means 80 of light springs 15 held in a strip of metal 16 lying along one side of the coin slot, and these springs while fairly strong yield to the su- 85 perior force of the powerful magnets intended to be used, thus insuring that no small magnets as used by children could open the lock, even though a child knew where to apply the magnets and which is not likely.

The spacing blocks 7 and 8 are preferably 90 also of non-magnetic material so as not to influence the sliding of the bolts should the latter retain any residual magnetism.

The coin slot 4 is of the usual construction 95 adapted to receive which ever maximum size coin the bank is designed for, and it is here shown with a pivoted side plate 17 normally closing the slot, through the action of a small spring 18.

Thus it will be seen that after coins are 100 placed in the bank, they cannot be taken out except by opening the main door, and the door can only be opened by the application of magnets to a plurality of special points at the outside of the shell of the device, also 105 that the form of the device suggests standing it on the flat end with the result that it protects it against the gradual entry of dust and also gives it the appearance of a paper weight quite free from resemblance to a bank, thus 110

giving an additional measure of security to its contents.

I claim:

1. A cylindrical bank having a spring actuated door in its flat surface, adapted to swing it to open position when released, locks having spring-projected bolts for locking said door, said locks being movable into unlocking position by magnets disposed exteriorly of the 10 casing and in alignment with the movement of said locks.

2. A bank comprising a casing having a

cylindrical wall and a bottom, a door for said bottom and swingable into open position when released, a pair of locks for said door 15 and disposed in a chord cutting the circular bottom on a line other than the diameter, spring means for urging said locks into locking position, said locks being moved into open position by magnets when the latter are disposed adjacent to the exterior surface of said casing and in a position coinciding with the chord common to both locks.

CARL W. CHERRY.
